(57) **CLAIM**

The ornamental design for a switch with book-shaped packaging, as shown and described.

DESCRIPTION

FIG. 1 is a perspective view of the switch with book-shaped packaging showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an exploded perspective view thereof;

FIG. 9 is an exploded perspective view thereof, shown in environmental use;

FIG. 10 is a perspective view thereof, shown in closed position;

FIG. 11 is a front elevational view of FIG. 10;

FIG. 12 is a rear elevational view of FIG. 10;

FIG. 13 is a left side elevational view of FIG. 10';

FIG. 14 is a right side elevational view of FIG. 10';

FIG. 15 is a top plan view of FIG. 10';

FIG. 16 is a bottom plan view of FIG. 10'; and,

FIG. 17 is a perspective view thereof, shown without a switch for clarity.

The broken lines indicate unclaimed portions and environment and form no part of the claimed design.

1 Claim, 17 Drawing Sheets
